UNITED STATES PATENT OFFICE.

CHARLES D. McDONALD, OF CHICAGO, ILLINOIS.

ATTACHMENT FOR EJECTORS OF DIE-PRESSES OR LIKE MACHINES.

1,243,435.

Specification of Letters Patent. Patented Oct. 16, 1917.

Application filed February 23, 1917. Serial No. 150,446.

To all whom it may concern:

Be it known that I, CHARLES D. McDONALD, a citizen of the United States, residing at Chicago, in the county of Cook and State 5 of Illinois, have invented certain new and useful Improvements in Attachments for Ejectors of Die-Presses or like Machines, of which the following is a specification.

The present invention relates to a certain 10 appliance or attachment adapted to be used in connection with ejectors of die-presses or like machines, whereby when the ejector is prevented from performing its ejecting action, the power will be automatically cut 15 off from the power shaft of the press and the entire press mechanism brought to a stand-still.

One object of the invention is to provide 20 certain movable parts which will be automatically set in motion when the ejector encounters a resistance to its normal movements and is thereby prevented from performing its ejecting operation. Upon the parts being so set in movement, they will act 25 to throw certain mechanism and cut off the supply of power from the power shaft, whereby the entire mechanism is stopped.

A further object of the invention is to 30 provide tension or similar means which will act to prevent operation of the appliance that cuts off the power when the normal pressure is exerted on the ejector during its ejecting operation, and so insures the power cutting-off appliance being operated only at 35 such times as when the ejector shall encounter an abnormal resistance in carrying out the ejecting operation.

A further object of the invention is to 40 movably mount the cam-member which moves the ejector in the ejecting operation, whereby when the ejector encounters an abnormal resistance, the pressure of this resistance will cause the cam-member to move, and then through a suitable connection, the 45 appliance will be operated to cut off the power from the power shaft.

A further object of the invention is to 50 provide a connection between the cam-member, moved directly by the ejector, and the appliance which cuts off the supply of power from the main power shaft of the press, whereby the movement of the cam-member will be amplified in transmission to the appliance which cuts off the supply of power 55 from the power shaft, so that sufficient pressure will be obtained to actuate the latter

parts without placing any undue strain or pressure upon the ejector when it moves the cam-member.

The invention further consists in the features of construction and combination of parts hereinafter described and claimed.

In the drawings:

Figure 1 is a front view of an automatic press mechanism equipped with the appliances of the present invention, and showing the said appliances in the position assumed when the ejector is working normally;

Fig. 2, a detail showing a portion of the parts illustrated in Fig. 1, and showing such parts in the position assumed when the ejector encounters an abnormal resistance to its ejecting operation and has acted to move the cam-member;

Fig. 3, a view of the appliance for cutting off the supply of power from the power shaft, and with the parts in the position assumed when power is being transmitted to said power shaft and the press in condition for running;

Fig. 4, a view similar to Fig. 3, showing the parts in the position assumed when power is cut off from the power shaft and the action of the press stopped;

Fig. 5, a detail showing a side view of the connection between the ejector and the cross-shaft which operates the appliance for cutting off the supply of power from the power shaft;

Fig. 6, a plan view of the clutch mechanism shown;

Fig. 7, a face view of such mechanism;

Fig. 8, a detail, partly in section, showing the clutch-pin and the clutch-pin actuating arms; and

Fig. 9, a detail showing one of said clutch-pin actuating arms.

In the art to which the present invention relates, an ejector is used for forcing the work out of the die after the stamping operation. It happens that, for one reason or another, the work will become choked in the die to the extent that the ejector mechanism cannot force it out, or only forces it partly out. If the press continues to operate after the ejector has failed to force the work out from the die, it is obvious that further choking of the die will result, which often-times places a strain upon the mechanism so as to cause serious injury to certain of the working parts.

It is the primary object of the present in-

vention to provide an appliance or device whereby when the ejector encounters a resistance to its normal operation, the presence of such resistance will actuate said appliance so as to cut off power from the power shaft and bring the entire press to a stop, thereby eliminating the heretofore-recited objectionable feature of allowing the press to continue in operation after the die has 10 become choked through failure of the ejector to force the work out therefrom.

Referring now to the drawings, the appliance is shown in connection with a press body 10, which may be of any suitable size 15 or form. A reciprocating die member 11 is shown, and, as illustrated, this die member is actuated by means of a toggle such as is fully shown and described in my co-pending application Serial No. 150,445, filed 20 February 23, 1917 and entitled "Appliances for die-presses or the like."

It is, of course, understood that the appliance of the present invention is not intended to be limited for use in connection with a press wherein the die is actuated by means 25 of a toggle, and the same is merely shown in order to illustrate one form of press with which the appliance of the present invention is applicable.

Carried by the reciprocating slide 12 of the die is an ejector 13 in the form of a lever, pivoted upon a pin 14, and comprising an acting end 15, and carrying a roller or similar member 16 at the opposite end. This 35 roller 16 travels along the cam-face 17 of a block 18. The block is held stationary with respect to the up and down movements of the die, and at a certain point in the upward movement of the die, the roller will 40 strike the sloping portion of the cam-face 17, which will cause the ejector to be moved so that the acting end 15 will be forced in a downward direction and eject the work from the die member.

The block 18, in the construction shown, is carried by a frame 19, which is pivotally mounted upon a pin 20. The upper end of the frame is formed with a lug or extension 21 provided with a slot 22, in which extends a limiting pin 23; and bearing against the outer face of this lug 21 is a spring 24 held within a suitable barrel or casing 25. This spring 24 is of sufficient strength so as to prevent the frame 19 from moving when 50 pressure is exerted against the cam-face of the block 18 during the normal operation of the ejector. Obviously, the said cam-face could not act to move the ejector in the ejecting operation unless the block 18 remained stationary. Therefore, the spring 24 is of sufficient strength so as not to allow the block to move except under abnormal 55 pressure.

Mounted upon the press body, adjacent 60 to the frame 19, is an ear or lug 26 carrying

a pin 27, upon which is mounted a bell-crank 28. One end 29 of this crank engages the outer side face of the frame 19. The other end 30 is connected to one end of a link or rod 31, which link or rod extends 70 downwardly and passes through an opening 32 in an arm 33 (see Fig. 5). A suitable nut or other abutment 34 is provided, whereby the rod 31 makes engagement with the arm 33 upon downward movement of the rod. 75 This arm 33 is keyed, or otherwise secured, to a cross-shaft 35, to the opposite end of which shaft is connected a lever 36 formed with a hand-piece 37. This lever, as shown, is limited in its up and down movements 80 by means of suitable stops 38.

Connected to the lever 36 by a pin 39 is a link 40, which in turn is connected to a rocking arm 41 and to one side of the pivot 42 for said arm. To the end 43 of this arm 85 41 is connected a link or rod 44, which actuates an expander 45 for brake members 46. To the opposite end 47 of the lever 41 is connected a link 48 joined to one end of a bell-crank 49, and the opposite end of said 90 crank is connected to a link 50, joined in turn to a clutch-pin actuating arm 51. This arm is pivoted upon a pin 52, and at its lower end is connected to a link 53, and this link in turn is joined to the lower end of a 95 clutch-pin actuating arm, which is pivoted at 55.

These clutch-pin actuating arms each embody a cam or wedge-shaped surface 56 (see Fig. 8), and when thrown inward toward 100 the main power shaft 57, they assume a position whereby they engage in a groove 58 formed in a spring-pressed pin 59, which pin is adapted to enter a recess in a collar 60 joined to a fly-wheel 61. This fly-wheel 105 is constantly driven, and when the pin is in engagement with the recess in the collar, power is being transmitted through the hub of the fly-wheel to the shaft 57, and when the clutch-pin actuating arms are thrown 110 into position so that the wedge-face 56 engages with the notch in the pin 59, the said pin is pulled outward from the recess in the collar and the connection to the power shaft 115 broken.

Although this form of clutch is desirable with presses in which the die is actuated with toggle mechanism, the particular form of clutch employed is not deemed in any way to be a limitation on the scope of the present invention, since, of course, the present invention may be employed in connection with clutches of an entirely different character. This particular form of clutch is shown because of the fact that it is especially desirable when a toggle action is employed for operating the die.

In stopping the machine, it should always be brought to rest when the die has reached the limit of its up-stroke. With the toggle 120

form of press, the die will reach this limit of up-stroke twice during each revolution of the power shaft; and by using two arms for actuating the clutch-pin, the power shaft 5 cannot move farther than one-half revolution after the clutch arms are set before the clutch-pin will be engaged. Hence, the power will be cut off when the die is at its limit of up-stroke, which occurs at the end 10 of each half revolution of the power shaft.

The operation briefly is as follows:

Assuming that the ejector 13 encounters a resistance whereby it cannot force the work from the die, such resistance will place a 15 back-pressure upon the ejector, whereby when it encounters the sloping portion of the cam-face 17, it will not be forced down, but, rather, the block 18, together with the frame 19, will be pushed back from the 20 ejector against the pressure of the spring 24. This is due to the pivotal mounting of the frame 19. When so pushed back as in Fig. 2, the bell-crank 28 will be rocked, pushing downward the rod 31, as shown by 25 dotted lines in Fig. 5, swinging the arm 33 to the dotted line position of Fig. 5, and rocking the cross shaft 35, which will move the lever 36 from the position of Fig. 3 to the position of Fig. 4. This will move up 30 the link 40 and move the rocking arm from the position shown in Fig. 3 to that shown in Fig. 4, actuating the link 44 to move the brake expander 45 and release the brakes to allow them to swing inward into operative 35 position; and the movement of the lever 41 will also move the rod 48, actuating the bell-crank 49, moving the clutch-pin actuating arm 51 inward, and through the instrumentality of the link 53, swing the clutch-pin 40 actuating arms 51 and 54 inward and place both arms in the position of Fig. 4. When so placed, they will be in position to withdraw the clutch-pin and cut off the application of power to the power shaft, thus 45 bringing the entire press mechanism to rest and preventing operation of the press after the die has become jammed.

I claim:

1. The combination with ejector mechanism, of a power shaft, means for controlling the application of power to said shaft, and means actuated by abnormal resistance to the operation of the ejector for operating said means for stopping the application of 55 said power from said power shaft, substantially as described.

2. The combination with ejector mechanism, of a power shaft, means for controlling the application of power to said shaft, 60 shiftable means for operating said power controlling means, a portion of said shiftable means being located adjacent the ejector mechanism and adapted to be moved when abnormal resistance to the operation 65 of the ejector is encountered, said movement

of said shiftable means operating said power controlling means to stop the application of power to said power shaft, substantially as described.

3. The combination with ejector mechanism, of a power shaft, means for controlling the application of power to said shaft, shiftable means for operating said power controlling means, a portion of said shiftable means being located adjacent the ejector mechanism and adapted to be moved 70 when abnormal resistance to the operation of the ejector is encountered, said movement of said shiftable means operating said power controlling means to stop the application of power to said power shaft, and means exerting a counterpressure upon said shiftable means to prevent movement of the latter during the normal operation of the ejector, 75 substantially as described.

4. The combination with ejector mechanism, of a power shaft, means for controlling the application of power to said shaft, shiftable means for operating said power controlling means, a portion of said shiftable means being located adjacent the ejector mechanism and adapted to be moved 80 when abnormal resistance to the operation of the ejector is encountered, said movement of said shiftable means operating said power controlling means to stop the application of power to said power shaft, and tension mechanism bearing against said shiftable means and preventing movement of said means during the normal operation of the 85 ejector, substantially as described.

5. The combination with ejector mechanism, of a power shaft, means for controlling the application of power to said shaft, means for operating said power controlling 90 means comprising a movable cam member with which the ejector engages, said cam-member being moved by pressure exerted on the ejector due to abnormal resistance to its operation, and a connection between said 95 cam-member and the means for controlling the application of power to said power shaft, substantially as described.

6. The combination with ejector mechanism, of a power shaft, means for controlling the application of power to said shaft, means for operating said power controlling 100 means comprising a movable cam-member with which the ejector engages, said cam-member being moved by pressure exerted on the ejector due to abnormal resistance to 105 its operation, a connection between said cam-member and the means for controlling the application of power to said power shaft, and means exerting a counterpressure 110 against said cam-member to prevent its moving during normal operation of the ejector, 115 substantially as described.

7. The combination with ejector mechanism, of a power shaft, means for control- 120

ling the application of power to said shaft, means for operating said power controlling means comprising a cam-member with which the ejector engages, a pivotal mounting for said cam-member located at one end thereof, said cam-member being moved about its pivot by pressure exerted on the ejector due to abnormal resistance to its operation, tension mechanism located at the opposite end 10 of the cam-member and exerting a counter-pressure to prevent movement of the cam-member during the normal operation of the ejector, and a connection between the cam-member and the means for controlling the 15 application of power to said power shaft, substantially as described.

8. The combination with ejector mechanism, of a power shaft, means for controlling the application of power to said shaft, 20 means for operating said power controlling means comprising a lever arm connected to said power controlling means, and means for actuating said lever arm operated by pressure exerted on the ejector due to abnormal 25 resistance to the movements thereof, substantially as described.

9. The combination with ejector mechanism, of a power shaft, means for controlling the application of power to said shaft, 30 means for operating said power controlling means comprising a rock-shaft, a connection between the rock-shaft and power controlling means for operating the controlling means by movement of the shaft, and means 35 for moving the shaft actuated by pressure exerted on the ejector due to abnormal resistance to its operation, substantially as described.

10. The combination with ejector mechanism, of a power shaft, means for controlling the application of power to said shaft, 40 means for operating said power controlling

means comprising a rock-shaft, two crank arms connected to said rock-shaft, a connection between one of said crank arms and 45 said power controlling means, and means for rocking said shaft to actuate said power controlling means, comprising a member operatively connected to the other crank arms, and said member being moved by pressure exerted on the ejector due to abnormal 50 resistance to its operation, substantially as described.

11. The combination with ejector mechanism, of a power shaft, means for controlling the application of power to said shaft, 55 means for operating said power controlling means, comprising a shiftable member, and a series of links and levers connecting the shiftable member and power controlling 60 means, said shiftable member being adapted to be moved when abnormal resistance to the operation of the ejector is encountered, and said links and levers serving to amplify the movement of the shiftable member in transmitting such movement to said power application controlling means, substantially as described.

12. The combination with ejector mechanism, of a power shaft, means for controlling the application of power to said shaft, 70 shiftable means for operating said power controlling means, a portion of said shiftable means being located adjacent the ejector mechanism and adapted to be moved 75 when abnormal resistance to the normal operation of the ejector is encountered, and said shiftable means being arranged to amplify the movement imparted thereto by the ejector mechanism in transmitting such 80 movement to the power controlling means for operating the latter, substantially as described.

CHARLES D. McDONALD.
